United States Patent Office.

WILLIAM SHEA AND L. D. HARVEY, OF HARVEY, MICHIGAN.

Letters Patent No. 79,866, dated July 14, 1868.

IMPROVEMENT IN FURNACES FOR MELTING METALS.

The Schedule referred to in these Letters Patent and making part of the same.

TO ALL WHOM IT MAY CONCERN:

Be it known that we, WILLIAM SHEA and L. D. HARVEY, of Harvey, in the county of Marquette, and in the State of Michigan, have invented certain new and useful Improvements in Furnaces; and do hereby declare that the following is a full, clear, and exact description thereof, reference being made to the accompanying drawings, and to the letters of reference marked thereon.

In the annexed drawings, forming part of this specification, A represents the brick-work of a furnace; B, the fore-bay; C, the hearth; D D, the tuyere-arches. Above these tuyere-arches are two protecting-plates, and below is one, marked, respectively, E, F, and G. These plates are made of cast iron, two inches thick, four feet long, and twenty or twenty-two inches wide, as the furnace may require, with a three-quarter inch pipe inside of the same, bent as represented in Figures 2 and 3. The pipes in each of the plates have two openings, one, H, being the feed-pipe that supplies the plates with cold water, and should have a stop-cock in the arch at some convenient place, to regulate the supply of water. The other opening, I, is a discharge-pipe, leading to any point to get rid of the waste water.

The plates E, F, and G are placed in the third course of brick, upright; G, below the tuyere-arch, and extended to protect the jambs; E and F above the tuyere, at convenient distance from each other, to cool the brick around the crucible. There are also two half-circle plates, J, with the same arrangement of pipes under the hearth. The pipes, when laid in brick-work, can be bent so as to come at any point that would be most convenient.

The advantages of this combination of plates and pipes are—

First, in making the plates in pieces, three for each tuyere-arch, the pipes will be short and not so liable to be stopped up with the water scalding.

Second, in case one plate should get stopped up, the rest of the plates will keep the hearth from burning out, which can be done by using more water in them, as there is a stop-cock on each feed-pipe.

Third, by using these plates one hearth can be made to last three times as long as one without them.

Fourth, by using these plates the crucible can at once be built and kept at the size of four or five feet in diameter, when in ordinary cases it is first built with a diameter of thirty to forty inches, and then burnt to the larger size before it makes iron fast and economical.

Having thus fully described our invention, and the advantages accruing therefrom, what we claim as new, and desire to secure by Letters Patent, is—

The putting of pipes into cast-iron plates, substantially as and for the purposes above set forth.

In testimony that we claim the foregoing, we have hereunto set our hands, this 16th day of November, 1867,

WILLIAM SHEA,
L. D. HARVEY.
